UNITED STATES PATENT OFFICE.

NILS M. ROSENDAHL, OF WATERLOO, IOWA, ASSIGNOR TO CONSTRUCTION MACHINERY COMPANY, A CORPORATION OF IOWA.

HOIST.

Application filed April 26, 1926. Serial No. 104,710.

This invention relates to hoists and has special reference to such mechanism particularly designed for use in raising and lowering loading hoppers or buckets for concrete mixers or the like where tip over or similar types of buckets are used.

The principal object of the invention is that of providing a dependable automatic clutch and brake mechanism for such hoists.

Other objects and advantages of the invention will appear in the further description thereof.

Referring now to the accompanying drawing, forming part of this application, and wherein like reference characters indicate like parts:

Figure 1 is a side elevation of a loading hopper and bucket as applied to a concrete mixer;

Figure 2 is an enlarged elevation, partly in section, of the upper end of the inclined track in which the bucket operates;

Figure 3 is a still further enlarged perspective view of the power releasing shoe of the bucket;

Figure 4 is a plan view in detail of the trip for the power releasing mechanism;

Figure 5 is a diagrammatic view of the power transmission unit with power applied to the drum;

Figure 6 is a view similar to Figure 4 showing the trip mechanism released; and

Figure 7 is a view similar to Figure 5 showing the power transmission mechanism in its opposite position.

1 represents the supporting frame of a concrete mixer, 2 the drum, and 3 the inclined track or ways for the loading hopper or skip 4, all of which are common in the art. The extreme upper end of the runway terminates in a horizontally disposed pocket-like structure 5, sufficiently large for the reception of the wheels 6 upon either side of the upper end of the skip 4, and into which the wheels roll when the skip is raised to its uppermost position by draft upon the line 7, the axle of the wheels in such position acting as the pivotal point of the skip so that as pull upon the line 7 is continued the skip will assume the position shown in dotted lines, Figure 1, and empty into the drum.

The hoisting line 7 is roved over any desired arrangement of sheave or sheaves, not shown, and leads to the hoisting drum 8 car-

ried upon the mixer and loosely mounted upon the power shaft 9. This drum is provided at one end with a band brake 10 and at the opposite end with the clutch mechanism 11; these two devices being cooperatively controlled by the hand lever 12, pivoted as at 13 and having connected thereto the rod 14 leading to the lever 15 mounted pivotally as at 16 substantially parallel with the lever 12, said rod 14 continuing on past the lever 15 as at 17, pivotally connected as at 18 to the bell crank 19 which is pivoted at 20 and its opposite arm attached as at 21 to the brake band 10, so that an extreme pull to the left, as viewed in the diagram, will apply the band and thus brake the drum 8.

The upper end of the lever 15 is connected in the usual manner as at 22 to the clutch mechanism 11, and is provided intermediate of said clutch mechanism and its connection 75 with the rod 14 with a contractile spring 23 fixed as at 24; this spring being for the purpose of applying a constant backward draft to the clutch lever 15, thus biasing same toward an inoperative position. However it is apparent that if the spring is allowed to fully function in holding the clutch in cooperative position the brake band 10 would be fully applied to the drum.

Now, for the automatic control of this mechanism, I provide a catch and trip device comprising a horizontally reciprocable rod 24, attached as at 25 to the upper end of the hand lever 12, the same being mounted in any convenient manner in the U-shaped frame 26 fixed adjacent the hand lever. On this rod 24 is attached as by the thumb screw 27 the block 28, it being so positioned that when the lever is thrown fully to the right, as shown in Figure 5, with the power applied to the drum and the brake released, it will catch behind the dog 29, pivotally mounted as at 30, said dog having vertically disposed fingers 31 upon either side of the rod 24 for pushing engagement with the rear end of the block 28 when the dog 29 is drawn away from engagement with the block. Such draft upon the dog 29 is accomplished by the rod 32 being attached thereto as at 33 and extending rearwardly 95 through the bearing post 34 and carrying upon its end the button 35 which is, at the time of the extreme elevation of the skip 4, engaged by the arcuately shaped fork 36, firmly attached to one of the side members 100 105 110

or angle irons 37 of the skip as at 38. As the skip approaches its fully elevated position the fork will straddle the rod 32 and engage the button 35, the action of which is clearly seen in Figure 2 of the drawings, and cause end draft to be applied thereto, drawing the dog 29 away from the block 28, and simultaneously pushing said block, by contact of the fingers 31, to the end, thus forcing the lever 12 outwardly or towards its centermost position, when, as is obvious, the spring 23 will be permitted to function and throw the lever 12 to its extreme outward or left position, which, as before stated, will disengage the clutch 11 from the drum 8 and simultaneously apply the band 10 braking the drum and holding the skip in its dumping position.

As suitable means for holding the dog 29 in operable position in respect to the block 28 I have provided an expansive helical spring 39 about the rod 32 engaging the post 34 at one end and a suitable collar 40 on the rod 32 at the other end.

From the foregoing it is evident that I have produced a simple and effective means whereby the batch skip of a mixer or other similarly operative device may be elevated by a single thrust of a control lever and its ultimate functioning left to the automatic operation of the mechanism. When repeated action is desired, requiring the lowering of the skip, the same is accomplished by manual manipulation of the lever 12 to its central position, at which time neither brake nor power will be applied, permitting the drum 8 to rotate freely upon its shaft, when, as is obvious, the gravitating of the skip will unwind the drum, the speed and action of same being conveniently controlled by said lever. It will be noted further that this mechanism is exceedingly simple in operation and the possibility of error on the part of the operator reduced to a minimum in that whether the skip is to be raised or lowered the operating lever is thrust in the same

direction, however but only slightly if lowering the bucket; whereas a full thrust of the lever must be accomplished to raise the bucket.

Having thus described my invention, what I claim and desire to secure by Letters Patent, is:

1. In a hoist, a lower terminal, an upper terminal an element to be raised and lowered intermediate of the terminals, a manually controlled hoisting mechanism for operating the element comprising a lever, a slideable member directly connected to the free end of said lever, a dog for normally holding the slideable member, and means carried by the element for disengaging the dog from the slideable member when said element is in its extreme elevated position.

2. A skip hoisting and control mechanism comprising a winding drum having a brake and operating clutch associated therewith, a hand lever for simultaneous control of the brake and clutch, a spring for normally holding the clutch disengaged and the brake engaged, means at the upper terminus of travel of the skip directly connected to the hand lever comprising a slideable block, a spring controlled dog for normally holding said block against movement, a rod for withdrawing the dog and means carried by the upper end of the skip for automatic engagement with the rod whereby when the skip is in its dumping position the dog will be withdrawn, the brake released, and the operating lever freed.

3. The combination with a concrete mixer including a skip having means for raising and lowering same, of a fork like element carried by the upper end of the skip for overreaching engagement with releasing mechanism for stopping the hoisting action of the skip.

In testimony whereof I hereunto affix my signature.

NILS M. ROENDAHL.
